UNITED STATES PATENT OFFICE.

GOTTLIEB U. MULLER, OF PHILADELPHIA, PENNSYLVANIA.

MONOPLANE.

1,098,962.

Specification of Letters Patent. Patented June 2, 1914.

Application filed July 23, 1913. Serial No. 780,629.

To all whom it may concern:

Be it known that I, GOTTLIEB U. MULLER, a citizen of the United States, residing in the city and county of Philadelphia, State of Pennsylvania, have invented a new and useful Monoplane, of which the following is a specification.

My invention consists of a monoplane provided with improved means for controlling 10 the movable sustaining planes to properly balance the machine when flying and control its movements of elevation and descent, as well as its lateral movements.

It further consists of means for controlling 15 the inclination of the movable sustaining planes from the seat of the operator to either move both in the same direction or one in one direction and the other in the opposite direction.

20 It further consists of improved means for horizontally steering the machine, whereby the rudder will not create cross-currents for the elevating plane and reduce its efficiency.

It further consists of an improved running gear capable to absorb intense shocks 25 and to withstand rough landing.

It further consists of other novel features of construction, all as will be hereinafter fully set forth.

30 The annexed drawings and the following description set forth in detail one mechanical form embodying the invention, such detail construction being but one of various mechanical forms in which the principle of 35 the invention may be used.

In said annexed drawings: Figure 1 represents a side-elevation of my improved monoplane. Fig. 2 represents a front-elevation of the machine with a portion of one of 40 the movable supporting planes broken away and removed. Fig. 3 represents a plan view of the machine with portions of the movable supporting planes broken away and removed, and with the engine, the propeller 45 and the support for said engine removed.

Fig. 4 represents a top plan view of the means for controlling the movable supporting planes. Fig. 5 represents a transverse section on the line $x-x$, in Fig. 4. Fig. 6 50 represents a detail view of the retracting means for one of the wheels. Fig. 7 represents a detail view of the elevation plane and its controlling means.

Similar numerals of reference indicate 55 corresponding parts in the figures.

Referring to the drawings, the reference

numerals 1 indicate the upper, parallel bars of the frames of the fuselage, which are connected at their rear ends to the rear ends of parallel bars, 2, somewhat shorter than said upper frame-bars. Upright struts, 3, connect the outer ends of the lower bars to the upper bars, and struts, 4, connect the bars intermediate said struts and the rear ends of the bars. The forward ends of the lower 60 bars are connected by a cross-bar, 5, and the upper bars are connected at the upper ends of the struts by means of a cross-bar, 6. Oblique braces, 7, extend from the lower cross-bar to the forward ends of the upper bars. Pairs 65 of arms, 8, are pivoted to the lower cross-bar, and arms, 9, are pivotally connected to a cross-bar, 10, which connects the lower, longitudinal frame-bars at the rear of the portion of the frame which forms the seat 70 and engine support. The arms 9 are tubular, and the shanks, 11, of forks, 12, slide in said forward ends of said tubular arms, and the axles, 13, of wheels, 14, are journaled in the ends of the branches of said 75 forks and of said pairs of arms. Coiled springs, 15, are secured to the forks and to the tubular arms, serving to retract the forks and wheels. A forwardly projecting and upwardly curved skid, 16, is supported between said wheels from the cross-bars of the truck-frame, to extend a distance above the level of the lower portions of the wheels. An arch, 17, is connected with the cross bar 80 10 at the rear portion of the truck portion 90 of the frame, and two longitudinal bed-bars, 18, are secured at their rear ends to the crown of said arch, and at their front ends to a support, 19, carried by the struts 40 which are part of the truck-portion of the frame, and a motor, 20, is supported upon said arch and support. A propeller, 21, is secured upon the shaft, 22, of said motor to rotate between the side-bars of the frame 95 to the rear of the truck-frame. 100

The motor may be of any type, and be controlled in any manner within convenient reach of the aviator, all of which, being within the selection of the builder, are not 105 illustrated.

The forwardly extending plane 23 is a part of the movable supporting planes removed from the center, and extending some distance to the front to provide an additional center of pressure to the one of the 110 movable supporting planes for natural stability, and also provide a bracing for the

movable supporting planes, as well as for the fuselage, said plane is secured by the ends of its forward cross-bar to the forward ends of the upper side-bars of the frames 5 and of the oblique braces, and extend rearward to be secured with its side bars to the struts 3, to the required angle of incidence. Two guide-bars, 24, are secured at their forward and rear ends to the forward and rear 10 cross-bars of the truck portion, and a carriage, 25, is slidable upon said guide-bars, and a pulley, 26, is journaled upon said carriage and has a worm-gear, 27, upon its upper side. A screw-shaft, 28, is journaled 15 in bearings, 29, upon the cross-bars, between and parallel to the guide-bars, and is threaded through an ear, 30, projecting from the under side of the carriage, and a hand-wheel, 31, is secured upon said screw-shaft to rotate the same. Said wheel is preferably beneath the seat, 32, for the aviator, which is supported at the forward edge of the truck-frame and above said guides and screw-shaft. An additional seat, not 20 shown on the drawings, may be placed on the bed bars 18 immediately in front of the motor for an attendant accessible to said motor.

Movable supporting planes, 33, are pivotally connected at the inner ends of their 30 forward spars, 34, to the upper ends of the forward struts and to the upper cross-bar of the frame. Said planes have each a rear spar, 35, and a central spar, 36, and are 35 otherwise braced and covered in any suitable or preferred manner. Upright struts, 37, are secured to the inner ends of the central spars of the planes and extend upward and downward, and brace-wires, 38, are secured to the ends of said struts and to various points of the frame-work of the planes. Brace-wires, 39, extend from the forward 40 ends of the upper side-bars of the frame to the forward spars of the planes. Upright struts, 40, are supported at the forward portion of the truck-frame, and are connected to upper cross-bar 6 of the fuselage, and guy-wires, 41, connect the upper 45 ends of said struts and extend to the forward spars of the planes. Slightly rearwardly inclined struts or guide-strips, 42, are secured at their ends to the upper and lower side-bars of the frame, and guide-bails, 43, upon the inner edges of the 50 movable sustaining planes are slidable upon said struts or strips. The lower ends of the actuating-struts 37 of the movable sustaining planes are movable in guides, 44, upon the sides of the lower side-bars of the fuselage, 55 so that said struts may be drawn forward and back and thus rock the movable sustaining planes. 37^x designates a bar carried by each of the struts 37, and extending therefrom, and each having brace-wires, 55, 60 secured to them and connected to the ends

of the actuating struts, 37, to equalize the outward strain of the planes and prevent buckling of the struts under such strain.

An elevation-plane, 45, has the ends of its forward cross-bar, 46, pivoted in brackets, 47, upon short struts, 48, connecting the upper and lower side-bars of the tail, near their rear ends, and a rock-shaft, 49, is journaled at the joined rear ends of the side-bars of the tail and has rearwardly-projecting arms 50, having slide-links, 51 pivoted at their outer ends, which links are slidable upon rods, 52, upon the upper side of the plane. An arm, 53, projects forward from one end of the rock-shaft, and the ends of wires, 54, or similar flexible connections are secured to the end of said arm, which wires pass around pulleys, 56, toward the forward end of the machine where they pass around and are secured to a pulley, 57, upon an upright shaft, 58, journaled in the front of the truck-frame and in front of the aviator's seat, and provided at its upper end with a hand-wheel, 59, for rotating it. A wire, 59, or similar flexible connection, is secured 80 from opposite sides to the lower end of one of the actuating struts of the movable sustaining planes on one side of the machine and passes around the pulley 60 and 61, journaled in the corners of the truck-frame, and around pulleys, 62 and 63, at the front and rear end of the guides for the carriage, while wires 59^x or similar flexible connections, are secured from opposite sides of the lower end of the other of the actuating struts of the movable sustaining planes upon the opposite side of the machine and passes around the pulleys 60 and 61 journaled in the corners of the truck-frame, and around pulleys 62 and 63, at the front and 90 rear ends of the guides for the carriage. The ends of said wires are wound in opposite directions around the pulley 60 upon the carriage, and secured to the same, so that rotation of said pulley in one direction 100 will pull upon one wire to draw the rear edge of one movable sustaining plane upward, while the rear edge of the other movable sustaining plane is pulled downwardly and vice versa. The rotation of the pulley 110 is accomplished by means of a worm, 64, rotatable with and slidable upon a shaft 65, journaled above one of the carriage-guides, and said shaft has a pulley, 66, upon its forward end, around which passes a sprocket-chain or similar flexible driving means, 67, which passes around an idler, 68, and around a drum or pulley, 69, upon a sleeve, 70, rotatably supported upon the shaft 58, and having a hand-wheel, 80.

Rudders, 71, are pivotally supported upon the outer sides of the rear portions of the side-bars of the fuselage, near the rear ends of the same, and springs, 72, secured to said rudders and to brackets, 73, upon the for- 120 125 130

ward rock-shaft of the elevation plane, serve to draw such rudders toward the sides of the frame. Brackets, 74, project from the outer sides of said rudders, and wires 81, are connected to such brackets and carried around pulleys, 75, at opposite sides of the truck-frame to pulleys, 76, in the truck-frame, and thence to foot-levers, 82, preferably fulcrumed upon the supporting frame, 77, of the forward skid, within convenient reach of the aviator when seated in the seat of the machine. A pair of curved and rearwardly inclined skids, 78, are secured beneath and to the rear portions of the side-bars of the fuselage, and have upright braces 79. In practice, the forward plane is set at the proper angle whereupon it is permanently secured to the upright struts 3. Having the movable sustaining planes set to be in perpendicular line with each other, and the elevating plane set to the starting position, completes the machine for the ascent, the aviator takes his seat, takes hold on the hand wheels and raises in the air, after flying a short distance he will be aware where readjustment of the machine is needed, and by means of the hand wheel 31, under his seat and the hand wheel in front of him he balances the machine until it flies steady. Any lateral unbalancing of the machine may be corrected by means of the lower hand-wheel in front of him, which changes the angle of incidence of the movable sustaining planes inversely, consequently will raise the lower side of the machine if the angle of incidence of that plane is increased. Any unbalancing longitudinally of the machine through loss of weight, for instance, loss of fuel or loss of explosives carried for destruction purposes, or in case of an accident, can be corrected by the hand wheel 31 on the screw-shaft under the aviator's seat. The head resistance of the movable sustaining planes can also be regulated by means of the hand-wheel 31 to balance the gravity of the machine with the speed obtainable, that is, without endangering the range of the elevating plane.

In order to guide the machine horizontally, the rudders are operated by suitable actuation of the pedals 82 by the operator, and in order to ascend or descend, the elevating plane 45 is varied by means of the hand wheel 83 which actuates the drum 57 around which is wound the wires 54 which are connected, as explained, with the elevating plane 45, to vary the inclination thereof.

In order to vary the angle of incidence of the movable sustaining planes, it will be understood that the rear portion thereof may be moved upwardly or downwardly in unison, or the rear portion of one may be raised and the rear portion of the other lowered, or vice versa. To accomplish this, the hand wheel 80 is actuated; this rotates the sleeve

70 carrying the drum 69, around which passes the sprocket chains 67 which actuate the pulley 66 and so the shaft 65, which carries the worm 64 and so imparts rotation to the pulley 26 around which passes the wires 70 59 and 59^x, and as these are wound around the pulley 26 in opposite directions and are secured to the movable sustaining planes as described, one end of the wire 59 leading to one plane will be slackened, and the other 75 end of the wire 59 will be tightened, so moving the lower end of that plane in one direction and varying the inclination of the rear end of that sustaining plane, for example, raising it, while at the same time, the other 80 wire 59^x being wound around the pulley 26, the opposite direction from that of the wire 59, will exert a reverse pull upon its strut to move the lower end thereof to vary the inclination of its sustaining plane in the opposite direction from that of the first plane, that is, the rear of one plane will be elevated, while the other is lowered. Now in order to raise or lower the rear of both planes in unison, the operator rotates the wheel 31 and 90 so the shaft 28, this will impart lateral movement to the carriage 25 carrying the pulley 26, which movement will carry both wires 59 and 59^x, so that a similar end of each is slackened and the opposite end of each is tightened, thus exerting pull upon each strut in the same direction, so that the rear ends of the planes are raised or lowered in unison. By means of these adjustments 95 of the planes, the operator can bring the 100 machine to a level under varying conditions such as if the load is unequal or if variable air currents are met with. In turning or in making curves or spirals or where a certain amount of list toward the inner side of the 105 curve is required, the operator can control the same.

As the front plane is an advanced stationary part of the movable sustaining planes, and fills the space between the sustaining planes, a comparatively large supporting surface will be provided free from obstructive parts of the machine, such as the power-plant which blows the full force of air of the propeller against the body of 115 the machine, whereby the efficiency of the power-plant is reduced. By locating the power-plant in the rear of the front plane, the latter will shield the motor as well as a number of parts of the machine and reduce the head resistance of the same, and the propeller will be working in a free and undisturbed body of air, thus attaining its full efficiency, and will not create eddies under the planes of the machine. As the 120 steering rudders are to the sides of the elevation plane, they will not create deviation of the air current to said plane, as the two rudders act at the sides of the machine they will not retard the machine as much. When 130

individually acting, as if one rudder was placed in the center of the tail, as the retarding point is on one side the machine will, with less resistance turn around that point, 5 than if it was in the center. If the machine strikes the ground with an undue shock, the wheels will be forced forward until the shock is over, when the springs will again draw the wheels rearward and raise the 10 machine. If the shock is very intense and the wheels are forced so far forward as to cause the forward skid to come into action, the latter will take up the ultimate shock. The rear skids will support the tail of the 15 machine sufficiently high from the ground to admit of the elevation plane working freely at any angle while the machine is on the ground. The aviator directs lateral flight with his feet and balancing and elevation 20 mechanism is within easy reach of his hands, so that easy control of all operating parts is possible.

Other modes of applying the principle of my invention may be employed for the mode 25 herein explained. Change may therefore be made as regards the mechanism thus disclosed, provided the principles of construction set forth respectively, in the following claims are employed.

30 Having thus described my invention, what I claim as new and desire to secure by Letters Patent, is:—

1. In a flying machine, a fuselage, supporting planes pivoted upon the 35 said fuselage, actuating struts secured to said planes, a carriage movably mounted upon said fuselage, means for longitudinally moving said carriage, a rotatable member upon said carriage, means for rotating said 40 member, and flexible connections secured to said struts and having their ends secured to be wound around said rotatable member.

2. In a flying machine, a fuselage, supporting planes pivoted to the sides of said 45 fuselage, actuating struts secured to said planes, a carriage movably mounted upon said fuselage, means for longitudinally moving said carriage, a pulley upon said carriage, means for rotating said pulley, 50 and flexible connections secured to said struts and having their ends secured and wound in opposite directions around said pulley.

3. In a flying machine, a fuselage, supporting planes pivoted at the sides of said 55

fuselage, actuating struts suitably secured to said planes, guides for said struts, a carriage movably mounted upon said fuselage, means for longitudinally moving said carriage, a pulley upon said carriage, means for 60 rotating said pulley, and flexible connections secured to said struts and guided to have their ends secured to be wound around said pulley.

4. In a flying machine, a frame or fuselage, supporting planes pivoted at their inner forward corners to the sides of the upper part of said frame, actuating struts secured to the inner edges of said planes, a longitudinal guide in the lower part of said 70 frame, a carriage upon said guide, means for longitudinally moving said carriage, a pulley upon said carriage, means for rotating said pulley, and flexible connections secured to the lower ends of said struts and 75 guided to have their ends secured to be wound in opposite directions around said pulley.

5. In a flying machine, a frame or fuselage, supporting planes pivoted at their inner forward corners to the sides of the upper part of said frame, actuating struts secured to the inner edges of said planes, guides upon the sides of the lower part of said frame for the lower ends of said struts, 80 a longitudinal guide in the lower part of said frame, a carriage upon said guide, means for longitudinally moving said carriage, a pulley upon said carriage, means for rotating said pulley, and flexible connections secured to the lower ends of said 85 struts and guided to have their ends secured to be wound in opposite directions around said pulley.

6. In a flying machine, a frame or fuselage, supporting planes pivotally supported upon the upper part of said frame, actuating struts secured to said planes, a longitudinal guide on said frame, a carriage upon said guide, means for moving said carriage 100 on said guide, a pulley upon said carriage, means for rotating said pulley, and flexible connections secured to said struts and having their ends secured to be wound around said pulley. 95
